UNITED STATES PATENT OFFICE.

JOHN L. KOZMOUSKI, OF BOSTON, MASSACHUSETTS.

PORTABLE FIRE-EXTINGUISHER.

1,147,410.

Specification of Letters Patent.

Patented July 20, 1915.

Application filed October 7, 1914. Serial No. 865,408.

To all whom it may concern:

Be it known that I, JOHN L. KOZMOUSKI, a citizen of the United States, and a resident of Boston, in the county of Suffolk and State of Massachusetts, have invented a new and useful Improvement in Portable Fire-Extinguishers, of which the following is a specification.

My invention relates to portable fire extinguishers and its object is to improve and simplify the construction thereof and increase the efficiency of the same in the manner hereinafter set forth.

Illustrative embodiments of my invention are shown in the accompanying drawings, in which—

Figure 1 is a side elevation of my improved fire extinguisher; Fig. 2 is a longitudinal section; Fig. 3 is a longitudinal section on an enlarged scale of the discharge nozzle; Fig. 4 is an end view; Fig. 5 is a transverse section of a modification; Figs. 6 and 7 are end views of modified forms of the discharge nipple, and Fig. 8 is a plan view of one form of spring washer that may be employed in the piston-packing herein-after described.

In the particular drawings selected for more fully disclosing the principle of my invention, 1 represents a reservoir adapted to contain the fire-extinguishing fluid and associated in any convenient manner with one or more pump cylinders, herein shown as two in number, the said cylinders in the present case being arranged symmetrically with respect to said reservoir and extending throughout the entire length thereof. In Fig. 2 the cylinders 2 2' are attached to the exterior surface of the reservoir by soldering the same thereto, or by other suitable modes of attachment, and in Fig. 5 the corresponding cylinders 31 31' are shown attached to the interior surface of the reservoir. The upper ends of the cylinders are closed by caps 3 3' threaded thereto and bored to receive the piston rods. The lower ends of the cylinders are closed and communicate by means of ports 5 5' with the chamber 6 formed between the bottom 4 of the reservoir and the partition 7 which extends across the same a short distance above the bottom thereof. The valve 8 herein shown as tapering or cone-shaped, integral with or attached to the stem 9 which extends through the reservoir, is normally in engagement with a correspondingly shaped

valve seat in said partition, said valve stem being provided with a boss 10 threaded to the top of the reservoir and provided with a handle 11 whereby said stem may be rotated to adjust the position of the valve 8. When the said valve is in the position shown, the flange 12 covers the pin-holes 13, 13' in the top of the reservoir, and when the handle 11 is turned to raise the valve 8 from its seat, said pin-holes are uncovered and permit air to enter the reservoir.

The discharge nozzle 14, shown in detail in Fig. 3, is shown in the present embodiment of my invention as threaded to the bottom of the reservoir, the conical flange 15 making a water-tight joint with a correspondingly shaped seat. The valve 16, herein shown as a ball valve, is arranged to coöperate with a spherical valve seat 16' for the purpose of closing communication between the discharge orifice 23 and the chamber 6. The discharge nipple 17, which as shown, is threaded to the nozzle, is provided with a serrated inner edge 17' so that when the ball valve rests on said edge, liquid will flow from said chamber 6 through the discharge orifice.

The valve 18, herein shown as a cone valve, is normally pressed by the spring 19 into engagement with its seat 20 and the latter as shown is in screw-threaded engagement with the nozzle and preferably is provided with a gasket 21 of lead or similar material, so that when the nozzle, which is provided with flattened surfaces 14' to take the jaws of a wrench, is screwed into the bottom of the reservoir with the passageway 22 in alinement with the aperture in the partition 7, a water-tight joint will be formed between said valve seat and partition.

I prefer to provide the discharge nipple with an elongated flattened discharge orifice 23, so that the extinguishing fluid will be discharged in the form of a thin flat sheet which will cover a considerable area. The same result may be obtained, however, by providing said nipple with three small orifices 23'. I do not, however, limit myself to an orifice of any particular type and may, as shown in Fig. 6, employ a single round orifice 23''.

Each pump cylinder is provided with a piston rod 24 connected to the operating handle 25 at one end and having a plunger 30 30' of any suitable form secured to the

other end. In Fig. 2 I have shown details of the plunger packing which I prefer to use. This packing consists of two oppositely-arranged leather washers 27, 27, compressed between the nuts 28, 28, which are threaded to the piston rod, and interposed between each washer and its coöperating nut is a thin plate 29 of spring material, which in a manner that will be obvious, serves to force the washers against the walls of the cylinder and thereby prevent leakage past the piston.

Operation: To fill the reservoir, the stem 9 is unscrewed by turning the handle 11, the 15 nozzle is removed by means of a wrench or other suitable tool, the apparatus inverted and the stock or fire-extinguishing fluid 20 poured into the chamber 6. The valve 8 is then screwed down upon its seat and the nozzle replaced. The reservoir will thus 25 store the stock for an indefinite time without danger of evaporation or leakage. To use the extinguisher, the valve 8 is unseated by means of the handle 11 and the handle 30 25 is reciprocated until the contents of the reservoir have been discharged. On the up- 35 stroke of the plungers the valve 16 is seated, thereby closing communication from the discharge orifice 23 to the chamber 6 while the valve 18 is unseated and the liquid drawn 40 from the reservoir through the passageway 22 and into the pump cylinders by way of the ports 32 in the nozzle and the ports 5' between the chamber 6 and cylinders, re- 45 spectively. On the down-stroke the cone valve is seated thereby closing communication between the ports 32 and the reservoir, and the ball valve is unseated being forced 50 against the serrated edge 17' of the nipple, so that liquid will pass around the ball valve and out through the discharge orifice.

Having thus described one illustrative embodiment of my invention, without however limiting the same thereto, what I claim as new and desire to secure by Letters Patent 45 is—

1. A fire-extinguisher comprising in combination a reservoir, a partition extending across said reservoir near its lower end, a 50 pump cylinder secured to said reservoir and having its lower end in communication with

the chamber formed between said partition and the bottom of said reservoir, a discharge nozzle communicating with said reservoir and said chamber, oppositely-acting valves 55 in said discharge nozzle, and a plunger in said cylinder.

2. A fire-extinguisher comprising in combination a reservoir, a partition extending across said reservoir near its lower end, a 60 plurality of symmetrically-arranged pump cylinders secured to said reservoir and having their lower ends in communication with the chamber formed between said partition and the bottom of said reservoir, a discharge 65 nozzle communicating with said reservoir and said chamber, oppositely-acting valves in said discharge nozzle and a plunger in each of said cylinders.

3. A fire-extinguisher comprising in combination a reservoir, a partition extending across said reservoir near its lower end, a pump cylinder secured to said reservoir and communicating with the chamber formed between said partition and the bottom of 75 said reservoir, said partition being provided with a valve seat, a valve coöperating with said valve seat, and means exterior to said reservoir for adjusting the position of said valve.

4. A fire-extinguisher comprising in combination a reservoir, a partition extending across said reservoir near its lower end, a pump cylinder secured to said reservoir and communicating with the chamber formed 85 between said partition and the bottom of said reservoir, said partition being provided with a valve seat, a discharge nozzle secured to the bottom of said reservoir and having a passageway in alignment with said 90 valve seat, said discharge nozzle having a port communicating with said chamber, oppositely-acting valves in said discharge nozzle, and a plunger in said cylinder.

In testimony whereof, I have hereunto 95 subscribed my name this 6th day of October, 1914.

JOHN L. KOZMOUSKI.
